CLAIM

The ornamental design for a tire tread, as shown and described.

DESCRIPTION

FIG. 1 is a front elevational view of a tire tread showing my new design, it being understood that the pattern is repeated throughout the circumference thereof;

FIG. 2 is a perspective view thereof;

FIG. 3 is a side elevational view thereof; and,

FIG. 4 is an enlarged fragmentary front view thereof. The broken line showing of the tire sidewall in all four views of the drawing is for illustrative purposes only and forms no part of the claimed design.
